COMBINATION CONTROL DEVICE FOR
IRONERS

Joseph W. Jensen, Chicago, Ill., assignor to Electric Household Utilities Corporation, Chicago, Ill., a corporation of Illinois

Application June 3, 1936, Serial No. 83,237

18 Claims.

(Cl. 38—1)

This invention relates to improvements in combination knee and foot treadle mechanism for controlling the operation of domestic ironers.

One object of the invention is to provide a simple and efficient treadle mechanism for controlling the operation of ironer mechanisms, which is constructed and designed so that it may be used as a foot or knee treadle means, as desired.

10 A more specific object of the invention is to provide a treadle mechanism of the character indicated, which may be mounted in position on the ironer so as to be actuated by the knee of the operator, or which may be detached and placed 15 on the floor so as to be actuated by the operator's foot.

A still further object of the invention is to provide a treadle mechanism which, when arranged to be actuated by the knee of the operator, may be adjusted to various positions for the convenience of the operator.

Other objects of the invention will more clearly appear from the description and claims herein-after following.

25 In the drawings forming a part of this specification, Fig. 1 is a side elevational view of an ironer and an associated cabinet, illustrating my improvements in connection therewith, the ironer being shown as extended for use and the side 30 wall of the cabinet being partly broken away to disclose a portion of the mechanism contained therein.

Fig. 2 is a view, similar to Fig. 1, of the outer end portion of the baseboard which carries the 35 ironer mechanism proper, certain parts being broken away and others shown partly in vertical section.

Fig. 3 is an underneath view of the parts shown in Fig. 2, the baseboard being broken away.

40 Figs. 4 and 5 are transverse, vertical sectional views, corresponding respectively to the lines 4—4 and 5—5 of Fig. 1.

For purpose of illustration the present invention is herein disclosed in connection with a 45 folding type domestic ironer wherein the ironer mechanism is associated with a cabinet into which it may be folded to be stored while not in use. In said drawings, A indicates a cabinet of substantially rectangular boxlike form, and B an ironer 50 mechanism mounted on a baseboard 10, the ironer mechanism B together with the baseboard 10 being foldable as a unit into the cabinet when not in use. The ironer mechanism comprises a roll 11 and a cooperating shoe 12 carried by a 55 head or standard 13 mounted at the inner end

of the baseboard 10, as shown in Fig. 1. The ironer mechanism is driven by an electric motor housed in a casing 14 secured underneath the baseboard 10. The standard or head 13 contains suitable gearing for connecting the motor to the 5 ironer mechanism, having means associated therewith and also contained in the standard or head 13 for controlling operation of the ironer mechanism. This controlling means may be of any well known form for the purpose.

10 The cabinet A is provided with a door opening 114, through which the ironer unit passes in being moved into and out of the cabinet. Suitable means is provided for guiding the ironer unit during its movement into and out of the cabinet 15 to fold the unit in vertical position when moved completely into the cabinet and to unfold the same to the horizontal position shown in Fig. 1 when entirely withdrawn from the cabinet. The specific ironer mechanism and the means for 20 guiding the ironer unit in its movements need no further description as the guide means does not form a part of the present invention and the ironer mechanism forms a part of this invention only in so far as it is related to my improved combined treadle means. The specific form of ironer and the mechanism for guiding the same to folded and unfolded positions, as shown in the drawings, are fully and completely disclosed in co-pending application, Serial No. 32,267, filed July 30 25, 1935, to which reference may be had. However, it might be pointed out that the ironer unit is guided by rails 15 and 16, which are duplicated at opposite sides of the cabinet, links 17 and 18 cooperating with the rails 16 and supporting 30 struts 19 at opposite sides of the inner end of the baseboard 10 carrying rollers 20 traveling in the channels of the rails 15. It is further pointed out that in its extended operating position, as shown in Fig. 1, the inner end of the baseboard 10 is 35 supported from the rails 15 by the struts 19.

The outer end of the baseboard 10 is supported by a foldable hinged leg 21, which is folded against the under side of the baseboard 10 when the ironer unit is moved into the cabinet A, as described 45 in the co-pending application hereinbefore referred to. The folding of the leg 21 is automatically performed during movement of the ironer into the cabinet A and any suitable mechanism may be employed for this purpose; therefore, this mechanism needs no further description. The mechanism indicated in Fig. 1 includes 50 a link 22 connected to the leg 21 and operated by a cam 23 actuated by the link 17.

55 My improved combined knee and foot treadle

mechanism comprises broadly a combined support and guide 24 on the baseboard 10 of the ironer mechanism; a treadle member 25; and a flexible connection 26 between the treadle member 25 and the controlling means in the head or standard 13 of the ironer mechanism. The combined support and guide 24 is in the form of an elongated sheet metal plate, preferably made of spring material, secured to the underneath surface of the baseboard 10 adjacent to the end thereof which carries the hinged leg 21. The plate, which forms the combined support and guide 24, has downwardly extending longitudinal flanges 27-27 along opposite sides thereof, said flanges having right angular inturned lower edge portions 28-28. The side portions of the plate section of the member 24, together with the flanges 27-27 and the inturned ends 28-28, form channels on opposite sides of the combined support and guide member for a purpose hereinafter pointed out. Along the longitudinal center of the platelike portion of the combined support and guide 24 is provided a downwardly projecting, continuous corrugation 29 of substantially V-shaped cross section, as most clearly shown in Figs. 4 and 5. At the outer end of the combined support and guide 24, that is, the end adjacent to the leg 21 of the baseboard 10, the plate section is provided with a downwardly bowed portion 30, which forms an abutment or stop member. The portion 30 is preferably formed integral with the plate section of the combined support and guide member 24 and comprises a striplike portion formed by transversely slitting the end of the plate between the opposite sides thereof and displacing the strip section thus provided.

The treadle 25 may, of course, be an electrical control device in the event that the operating mechanism in the head 13 is electrically operated. In the structure shown in the drawings, however, the invention is illustrated in connection with a mechanical control in which the treadle and the ironer head are connected by a flexible mechanical connection 26.

The treadle member 25 comprises a base 31 having a treadle plate 32 pivoted thereon, as indicated at 33. The base 31 includes a heavy supporting plate member 34, which rests on the floor when the treadle member is employed for foot operation. The supporting plate 34 is provided with a pair of supporting buttons 35-35 at one end thereof, as clearly shown in Figs. 1, 2, 3, and 4, which are made of rubber and hold the treadle member against slipping while supported on the floor. The rubber buttons 35-35 have rounded end portions 36-36, which project through the supporting plate 34 to secure the buttons in place. The treadle plate 32 is in the form of a hollow cap and embraces the upstanding portion of the base 31. The treadle plate 32 is designed to conform to the foot of the operator and is provided with the usual depressed heel-receiving portion 37.

The flexible connection 26 between the head 13 of the ironer mechanism and the treadle member 25 is of well known form and includes an outer flexible conduit, which contains a flexible rod or wire 38, shown in Figs. 2 and 3, which is freely slidable lengthwise in the conduit. As is well understood, the flexible rod or wire 38 is connected to the treadle member 25 so that when the treadle plate 32 is depressed, the wire will be pulled in one direction, and when the treadle plate 32 is raised, will move in a reverse direction. This reciprocating motion of the wire 38 is

communicated to the controlling mechanism contained in the standard or head 13 in a well known manner to throw the ironer mechanism into operation when the treadle plate 32 is depressed and to throw the same out of operation when the treadle plate is permitted to rise. The treadle plate 32 is automatically returned to its raised position by the usual spring means, thereby also effecting return movement of the flexible rod or wire 38. As shown most clearly in Figs. 3 and 4, the supporting plate 34 of the base member 31 has a widened section 39, which is of substantially rectangular form and of such a width as to engage within the guide channels formed by the flanges 27-27 of the combined support and guide member 24, as shown in Figs. 3 and 4. The treadle member 25 is attached to the baseboard 10 of the ironer mechanism in inverted position by engaging the same with the combined support and guide member 24. In engaging the treadle member 25 with said combined support and guide member 24, the platelike support 34 of the base member 31 is entered into the channels of the combined support and guide member 24 at the left-hand end of the latter, as shown in Figs. 2 and 3. As will be clear upon reference to Figs. 1, 2, and 3, the combined support and guide member 24 is of such a length that the treadle member may be adjusted to several different positions lengthwise thereof, two of such positions being indicated in dotted lines and designated by 40 and 41 respectively. The supporting plate 34, when engaged with the guide channels of the combined support and guide member 24, is yieldingly clamped between the inturned ends 28-28 of the flanges 27-27 and the corrugation 29 and is thus retained in adjusted position by the friction between these parts. When the treadle member 25 is adjusted to the position indicated by the dotted line 40, same will be held against endwise movement by engagement with the stop 30.

As will be evident from the preceding description taken in connection with the drawings, the treadle member 25 of my improved combined knee and foot treadle mechanism may be readily converted from one form to the other. When the ironer is not in use, the treadle member 25 is preferably attached to and supported by the combined support and guide member 24 and occupies this position on the baseboard 10 when the ironer is stored within the cabinet A. In employing the treadle member 25 for knee operation, the same is supported by the combined support and guide member 24, as shown in Figs. 1, 2, 3, and 4, in which position it may be readily engaged by the knee of the operator to properly actuate the treadle plate 32 to start, stop, and control the operation of the ironer mechanism. As hereinbefore pointed out, the treadle member 25 may be adjusted to numerous positions along the combined support and guide member 24 to suit the convenience of the operator. When it is desired to employ the treadle member 25 for foot operation, it is merely detached from the combined support and guide member by sliding the supporting plate 34 of the treadle member out of the guide channels and, after inverting the treadle member 25, placing the same on the floor, as shown in Fig. 1.

I have herein shown and described what I now consider the preferred manner of carrying out my invention, but the same is merely illustrative and I contemplate all changes and modifications that come within the scope of the claims appended hereto.

I claim:

1. In an ironer mechanism, the combination with a power-driven ironer; of a support for said ironer, on which said ironer is mounted; a treadle member for controlling the operation of said ironer, said treadle member having a base portion for supporting the same on the floor for foot operation; and clamping means on said support for detachably holding said treadle member in position for knee operation.
2. In an ironer mechanism, the combination with a power-driven ironer; of a support for said ironer; a treadle member for controlling the operation of said ironer, said treadle member having a base portion for supporting the same on the floor for foot operation; and cooperating means on said support and base portion of the treadle member for suspending the treadle member in position on the support for knee operation.
3. In an ironer mechanism, the combination with a power-driven ironer; of supporting means for said ironer including a baseboard carrying the ironer; means for controlling the operation of the ironer including a treadle member and a flexible actuating connection between said treadle member and ironer, said treadle member having a base portion for supporting the same on the floor for foot operation; and means for detachably connecting the treadle member in inverted position to the underneath side of the baseboard, said means including a bracket fixed to the baseboard for detachably receiving the base portion of said treadle member.
4. In an ironer mechanism, the combination with a power-driven ironer; of an elevated supporting baseboard for said ironer; a treadle member for controlling the operation of said ironer; means for detachably clamping said treadle member underneath said baseboard for knee operation; and actuating means permanently connecting said ironer and treadle member for controlling the operation of said ironer through actuation of the treadle member, said connecting actuating means being flexible to permit movement of said treadle member from its operating position on said baseboard to operating position on the floor without disturbing the operative connection between said treadle member and ironer.
5. The combination of a power-driven mechanism, an elevated support on which said mechanism is mounted; convertible treadle means, and means for readily detachably securing the treadle means to the support, whereby the treadle means may be positioned for either knee or foot operation for controlling the operation of said mechanism.
6. In an ironer mechanism, the combination with a power-driven ironer; of supporting means for said ironer including a baseboard; means for controlling the operation of said ironer including a treadle member; a base on said treadle member for supporting the same on the floor for foot operation, said base having lateral flangelike portions; and a supporting bracket fixed to the baseboard, said supporting bracket having side channels within which said flangelike portions of the base of the treadle member are engageable to support the latter in inverted position for knee operation.
7. In a mechanism of the character described, the combination with a power-driven operating mechanism; of supporting means for said operating mechanism including an elevated baseboard on which said operating mechanism is
- mounted; means for controlling the operation of said operating mechanism including a treadle member, said treadle member having a base portion adapted to rest on the floor for supporting the treadle member for foot operation; and means on said baseboard for supporting said treadle member for knee operation comprising a bracket having a pocket receiving the base portion of said treadle member.
8. In a mechanism of the character described, the combination with a power-driven operating mechanism; of supporting means for said operating mechanism including an elevated baseboard on which said operating mechanism is mounted; means for controlling the operation of said operating mechanism including a treadle member, said treadle member having a base portion adapted to rest on the floor for supporting the treadle member for foot operation; and means on said baseboard for supporting said treadle member for knee operation comprising a bracket having a pocket receiving the base portion of said treadle member, said pocket being provided with supporting guide portions for said base portion in various positions of adjustment lengthwise of said bracket.
9. In a mechanism of the character described, the combination with a power-driven operating mechanism; of supporting means for said operating mechanism including an elevated baseboard on which said operating mechanism is mounted; means for controlling the operation of said operating mechanism including a treadle member, said treadle member having a base portion adapted to rest on the floor for supporting the treadle member for foot operation; and a bracket fixed to the underneath side of said baseboard for detachably supporting said treadle member in position for knee operation, said bracket including means frictionally engaging said base portion to hold the same in adjusted position.
10. In a mechanism of the character described, the combination with a power-driven operating mechanism; of supporting means for said operating mechanism including an elevated baseboard on which said operating mechanism is mounted; means for controlling the operation of said operating mechanism including a treadle member, said treadle member having a base portion adapted to rest on the floor for supporting the treadle member for foot operation; and a bracket fixed to the underneath side of said baseboard for supporting said treadle member for knee operation, said bracket having means thereon frictionally gripping said base portion to resist movement thereof along said bracket, said treadle member being adjustable lengthwise of said bracket.
11. In a mechanism of the character described, the combination with a power-driven operating mechanism; of supporting means for said operating mechanism including an elevated baseboard on which said operating mechanism is mounted; means for controlling the operation of said operating mechanism including a treadle member, said treadle member having a base member adapted to rest on the floor to support the treadle member for foot operation, said base member having a platelike bottom portion; and a supporting member fixed to the underneath side of said baseboard, said supporting member having opposed guide means adapted to receive the platelike portion of the base member to support

said treadle member from said baseboard for knee operation.

12. In a mechanism of the character described, the combination with a power-driven operating mechanism; of supporting means for said operating mechanism including an elevated baseboard on which said operating mechanism is mounted; means for controlling the operation of said operating mechanism including a treadle member, said treadle member having a base member adapted to rest on the floor to support the treadle member for foot operation, said base member having a platelike bottom portion; and a supporting member fixed to the underneath side of said baseboard, said supporting member having inwardly extending supporting flanges at opposite sides thereof adapted to receive and support said platelike portion of the base member to support the treadle member for knee operation.

13. In a mechanism of the character described, the combination with a power-driven operating mechanism; of supporting means for said operating mechanism including an elevated baseboard on which said operating mechanism is mounted; means for controlling the operation of said operating mechanism including a treadle member, said treadle member having a base member adapted to rest on the floor to support the treadle member for foot operation, said base member having a platelike bottom portion; and a supporting plate member fixed to the underneath side of said baseboard, said plate member having supporting flanges at opposite sides thereof and a central depending guide portion between and above said flanges, said flanges and guide portion being adapted to receive said platelike portion of the base member therebetween for frictionally holding said treadle member in position for knee operation.

14. In a mechanism of the character described, the combination with a power-driven operating mechanism; of supporting means for said operating mechanism including an elevated baseboard on which said operating mechanism is mounted; means for controlling the operation of said operating mechanism including a treadle member, said treadle member having a base member adapted to rest on the floor to support the treadle member for foot operation, said base member having a platelike bottom portion; and a supporting plate member fixed to the underneath side of said baseboard, said plate member having supporting flanges at opposite sides thereof and a central depending guide portion between and above said flanges, said flanges and guide portion being adapted to receive said platelike portion of the base member therebetween for frictionally holding said treadle member in position for knee operation, said platelike portion of the base member being slidable on said flanges lengthwise of the plate member for adjustment to various positions.

15. In a mechanism of the character described, the combination with a power-driven operating mechanism; of supporting means for said operating mechanism including an elevated baseboard on which said operating mechanism is mounted; means for controlling the operation of said operating mechanism including a treadle member, said treadle member having a base member adapted to rest on the floor to support the treadle member for foot operation, said base

member having a platelike bottom portion; a supporting plate member fixed to the underneath side of said baseboard, said plate member having supporting flanges at opposite sides thereof and a central depending guide portion between and above said flanges, said flanges and guide portion being adapted to receive said platelike portion of the base member therebetween for frictionally holding said treadle member in position for knee operation, said platelike portion of the base member being slidable on said flanges lengthwise of the plate member for adjustment to various positions; and stop means at one end of said plate member for limiting the sliding movement of said treadle member.

16. In a mechanism of the character described, the combination with a power-driven operating mechanism; of supporting means for said operating mechanism including an elevated baseboard on which said operating mechanism is mounted; means for controlling the operation of said operating mechanism including a treadle member, said treadle member having a base member adapted to rest on the floor to support the treadle member for foot operation, said base member having a platelike bottom portion; and a supporting spring plate member fixed to the underneath side of said baseboard, said spring plate member having horizontal supporting flanges at opposite sides thereof and a longitudinally extending, riblike, guide projection above and between said flanges, said flanges and guide projection being adapted to receive the platelike portion of the base member of the treadle member therebetween and frictionally grip said platelike portion to support the treadle member from the baseboard for knee operation.

17. In a foldway ironer mechanism, the combination with a cabinet; of a power-operated ironer mounted on a baseboard, said ironer and baseboard being movable into and out of the cabinet as a unit and being foldable within the cabinet for storage when not in use and being disposed in horizontal operating position when completely withdrawn from the cabinet, one end of said baseboard being supported by the cabinet and the other end thereof being supported by a foldable leg when the ironer is in operating position; means for controlling the operation of said ironer including a treadle member having a flexible operating connection with said ironer, said treadle member having a base portion for supporting the same on the floor for foot operation; and a supporting bracket underneath said baseboard and secured to the same, said bracket being pocketed to receive the base portion of said treadle member and support the latter for knee operation, said pocket also serving to support said treadle member on said baseboard when the ironer unit is folded into the cabinet for storage.

18. The combination with an ironer; of support means for the ironer; means for controlling the operation of the ironer, including a leg operated member; means for readily detachably securing said member to the support means; and means flexibly connecting the leg operated member and ironer, whereby said ironer may be operably controlled either by the knee, when the member is carried on the support means, or by the foot when said member is detached from the support means and resting on the floor.
